UNITED STATES PATENT OFFICE

2,004,681

SHUTTLE CHANGING LOOM

Lewis S. Vose, Worcester, Mass., assignor to
Crompton & Knowles Loom Works, Worcester,
Mass., a corporation of Massachusetts

Original application April 4, 1932, Serial No.
603,051. Divided and this application May 24,
1933, Serial No. 672,667

7 Claims. (Cl. 139—227)

This is a division of my application Serial No. 603,051.

This invention relates to shuttle changing looms and it is the general object of the invention to provide means to prevent resumption of weaving after a shuttle change if the pick laid by the outgoing shuttle be defective.

In weaving high grade fabrics a center filling stop motion is used so that each pick may be detected. When a "pick-out" is made, the short pick is removed and the pattern chain turned back to open the shed on the good pick preceding the defect. This pick has previously been beaten into the fell of the cloth and is therefore out of reach of the filling fork. The latter would therefore be unsupported and would act to stop the loom, even though a pick was in the shed. To prevent an unneeded stoppage there is provided a shield which moves in front of the knock-off notch when the loom stops, and deflects the dagger away from the notch on the first beat up after the "pick-out." On the following pick the stop motion is free to operate because of restoration of the shield to normal position.

Because of this characteristic of the center stop motion, the last flight of the outgoing shuttle of a loom which stops to change shuttles can lay a defective pick which will not be detected. On the first pick of the new shuttle there will be a whole pick in the shed, and the loom will continue to run. The mispick of the previous shuttle will therefore be incorporated into the fabric. It is accordingly an important object of my present invention to provide means which shall operate to prevent operation of the loom subsequent to transfer when the last pick laid by the outgoing shuttle is defective.

It is another important object of my invention to provide means for retaining tension on the weft at the time of shuttle change until the shed again crosses. In the type of loom to which my invention more particularly relates the shed is open during a shuttle changing operation and as a result of this condition there is the chance that the reserve bunch in the outgoing shuttle will be so small as to be entirely free from the shuttle before the latter comes to rest in the receiving box for exhausted shuttles. Under these conditions the tension of the weft caused by the shuttle eye is lost and a loose pick results. I provide means for clamping the weft so as to maintain the tension thereon until after the sheds have crossed subsequent to the resumption of weaving.

With these and other objects in view which

will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a loom having my invention applied thereto,

Fig. 2 is a detail view of parts of Fig. 1 on an enlarged scale,

Fig. 3 is a diagrammatic view of the structure shown in Fig. 2 but in a different position,

Fig. 4 is a top plan view of the loom looking in the direction of arrow 4, Fig. 1, on an enlarged scale,

Fig. 5 is a vertical section through the loom showing the center stop motion used with my invention, and

Fig. 6 is a vertical section on line 6—6 of Fig. 5.

Referring to the drawings, I have shown a breast beam 1, loom frame 2, and lay 3 pivoted at 4 and having swords 5. Shifting shuttle boxes not shown are located on the opposite side of the loom from that shown in Fig. 1. A change shaft 12 extends across the loom and performs the functions common to a similar shaft in the usual single color Stafford shuttle changing mechanism, such as is shown and described in United States Letters Patent No. 1,100,886 granted June 23, 1919, to S. S. Jackson. In the present instance, however, shaft 12 does additional work not called for in former Stafford changers.

A filling feeler mechanism, not shown herein but similar to that set forth in copending application Serial No. 603,051, of which this is a division, acts to stop the loom upon deficiency of filling, and start rotation of shaft 12, one complete rotation of which effects weft replenishment and starts the loom running again. When the change shaft 12 starts to rotate, box front 53 is raised by lifter 54 fulcrumed at 55 in stand 56 mounted on back of the lay. A cam 57 on shaft 12 effects this action by depressing lever 58 attached to lifter 54 by connector 60. Lever 58 is fulcrumed at 61 behind the shaft 12.

When the front 53 is elevated to an extent sufficient to permit ejection of a depleted shuttle, lifter 54 comes in contact with screw 62 on ejector lever 63, causing the latter to rock on shaft 64 mounted on a lay carried stand 56. The ejector lever 65 is thereupon moved forward beneath binder 66 to push against the lower back portion of the exhausted shuttle. The outgoing shuttle is thus projected forwardly off the lay to carry its weft.

thread toward the thread clamp to be described hereinafter.

A shuttle carrier 121 common to the stacks of shuttles, and normally in rear position, is moved by levers 128 secured to top shaft 129 when a shuttle change is to occur. A crank 130 on the shaft 129 is pivotally connected to a link 131, see Fig. 1, and reciprocated by a cam lever 132 pivoting about fixed center 61. The cam lever is actuated downwardly by a cam 133 on change shaft 12, and is raised by a spring 134. By this mechanism the lever 128 is first moved forwardly, or to the left as viewed in Figs. 1 and 2, and then rearwardly, for each shuttle changing operation.

The matter thus far described may be the same as that shown in the aforesaid application Serial No. 603,051.

To permit the weaving of fine fabrics, I employ a center filling stop motion. The lay has a stand 140, Figs. 5 and 6, to which is pivoted a dagger 141 weighted so that its front pointed end tends to rise. The filling fork has tines 142 movable about a lay carried pivot 143 and are secured to a small rocking element 144. A link 145 connects the element and dagger and a reciprocating rod 146 rises relatively to the lay every pick to raise the fork. The parts are so related that the dagger will be held down when weft is present, but will rise if weft be absent from the shed.

The shipper shaft 147 has fixed thereon a finger 148 supporting a flat spring 149. A stand 150 on the breast beam supports a stub shaft 151 on which rocks a transmitting arm 152 lying just behind finger 148. A notch 153 in the arm is adapted to receive the dagger 141 as the lay advances.

A shield 154 is loosely pivoted on shaft 151 and when down covers the notch. A resetting rod 155 is arranged to engage the lay when the shield is in the down position shown in Fig. 5 and thus rock the shield back to normal nonshielding weaving position as the lay advances on the first pick after the loom has been stopped. It should be noted that the dagger passes beyond the notch before the rod and lay coact to reset the shield, so that on the first pick after weaving is resumed the stop motion is incapable of stopping the loom should filling be absent from the shed. This is a normal operation necessitated by the conditions growing out of the correction of a mispick.

Fastened to the breast beam is a spring lock 156 which yields to allow a hub 157 on the shield to rise, the spring thereafter retaining the shield yieldingly raised. When the shipper shaft rocks counter-clockwise as viewed in Fig. 5, spring 149 will overpower spring 156 and move the shield down. The center stop motion is not new, and is set forth to illustrate a shielded type such as is found on certain looms.

The shield acts to permit the loom to restart after replenishment and continue running even though the last pick laid by the outgoing shuttle be defective, and to correct this undesirable condition I have provided the mechanism set forth herein to detect a mispick on the beat on which weaving is resumed. As shown herein I employ a side stop motion modified, if desired, as shown in the U. S. Patent No. 1,100,660 to Jackson, although the altered tines shown in that patent need not be used, since the center stop motion shown herein will detect weft independently of the side motion.

Side stop motions are well understood, and I show parts of one herein for purposes of illustration in Figs. 1, 2 and 4. The lay has a grid 160 along which the weft lies when the shuttle

is boxed at the magazine side of the loom. A tiltable fork 161 is pivoted to a slide 162 mounted for back and forth motion in a guide 163 on the breast beam. A loop 164 formed as part of the fork extends forwardly to coact with an actuator head 165 having a regular forward motion on alternate picks when the shuttle is boxed on the adjacent end of the lay.

When weft extends across the grid, the fork is tilted and the head moves forwardly with an idle stroke. Should the weft be absent, however, the fork remains in position to permit the head to engage the loop, after which continued forward motion of the head will cause the slide to advance. This results in forward movement of a knock-off lever 166 as will be understood by reference to Fig. 4 and there follows the customary movement of parts to stop the loom.

When the lay stops to replenish, the flat spring 149 on the shipper shaft lowers the shield to cover notch 153. When starting up after replenishment, therefore, the dagger 141, even though raised as a result of a defective pick, will be deflected away from the notch. The shield will be reset later in the forward beat of the lay, and it is during this interval that the side fork will operate to stop the loom. It is sufficient if the side fork operates only on replenishing beats of the lay, since the center motion detects every pick except the one when shuttle change occurs. When a defective pick is in the shed the lay will start up after replenishment, but will be stopped by the side fork.

Another feature of the invention relates to a thread clamp to preserve the tension of the last pick laid by the expelled shuttle. In bobbin changers the outgoing bobbin leaves the weft in the shuttle eye, thereby preserving the tension should the yarn unwind completely from the bobbin. Under similar circumstances in a shuttle changer, however, the yarn would pull out of the shuttle eye and the tension be lost.

To prevent this undesirable condition I form the inner magazine frame with a rear arm 175 and pivot thereon a bell crank lever 176 as at 177, see Figs. 1, 2, 3 and 4. An arm 178 rigid with a shuttle advancing arm 128 rocks with the latter at replenishment. An adjustable pin and slot connection between arm 178 and lever 176 moves the lower arm 179 of said lever. A clamp support 180 is pivoted to arm 179 at 181 and held yieldingly in the position shown in Fig. 2 by tension spring 182. Stops limit the amount of relative motion of the parts about pivot 181 under spring action.

A retaining hook 183 pivoted to the magazine M is positioned by a stop 184 and is freely movable upwardly. The lower end of the support 180 has fixed and pivoted clamping blades 185 and 186, respectively. The movable blade has a depending actuating closing finger 187 and an upper opening lug 188 for the hook 183, see Fig. 2.

Normally, the blades are in the closed position shown in Figs. 1 and 2 but at replenishment, with the lay at rest in rear position, the lever 128 will move forwardly as described in the aforesaid application Ser. No. 603,051 to move the shuttle carrier forwardly. At the same time, the clamp support 180 will move rearwardly, to the full line position in Fig. 3, slightly behind that shown in Fig. 2, causing the hook to open the frictionally held movable blade 186. This releases any previously held thread, and forms a notch 189 to receive the thread of the outgoing

shuttle. Continued rear motion of the support causes finger 187 to strike the temporarily stationary lay to return the movable blade to normal position relatively to the support, thereby 5 clamping the thread of the outgoing shuttle. This thread is later cut at the selvage.

As the lever arm 128 moves rearwardly to advance a new shuttle toward the lay the parts movable about pivot 177 return to their normal 10 forward position shown in Fig. 2, the hook camming up over and falling behind the lug 188. If there be no thread for the clamp to grasp, the side stop motion will stop further weaving, but if weft be present and held across the fork 15 by the clamp, conditions are proper for continued weaving, and the temporary disability of the fork to detect because of the clamped thread will do not harm.

From the foregoing it will be seen that I have 20 provided means effective to prevent continuance of weaving in a shuttle changing loom which stops to effect replenishment if the last pick laid by the outgoing shuttle be defective. Although the structure shown herein contemplates 25 a starting up of the loom which is to be immediately checked by the side stop motion, yet I do not wish to be limited to this arrangement inasmuch as I believe that I am the first to provide means to prevent the weaving of a mis- 30 pick in looms of this type where the fault is caused by the outgoing shuttle. It will also be seen that I have provided a clamp effective to retain the tension of the weft which extends through the shed when the latter is held open 35 with the lay temporarily at rest in back position for replenishment purposes. It will also be seen that the side stop motion and clamp are so related that if there be no thread to clamp the stop motion will be free to act, but that if thread 40 is present and is seized by the clamp the disability of the side stop motion would be of no consequence, since conditions are proper for continued weaving.

Having thus described my invention it will be 45 seen that changes and modifications may be made therein by those skilled in the art without departing from the spirit and scope of the invention and I do not wish to be limited to the details herein disclosed, but what I claim is:

50 1. In a shuttle changing loom which stops with the lay at back center to effect shuttle change, means to replace a depleted shuttle with a fresh shuttle and then resume weaving operations, a center filling stop motion to detect the condition 55 of weft in the shed every pick of the loom except the one immediately following the resumption of weaving, a thread clamp to hold the thread of the depleted shuttle after the latter has been ejected from the loom, and additional means to 60 detect the condition of weft held by the clamp on said pick and prevent continued running of the loom if the thread laid by the expelled shuttle fails to be held by the clamp.

2. In a shuttle changing loom which stops to 65 effect shuttle change, means to replace a depleted shuttle with a fresh shuttle while the loom is stopped and then resume weaving, a center stop motion normally operative every beat of the loom to detect the condition of weft in the shed, means 70 operative to disable said center stop motion when the loom stops to change shuttles and render the stop motion inoperative to stop the loom during the beat on which weaving is resumed, a thread clamp to preserve tension of the weft in the shed, 75 and means between the center stop motion and

the clamp to detect the condition of weft laid by the outgoing shuttle on alternate beats of the loom and on the beat when the center stop motion is disabled and prevent continued loom operation after resumption of weaving if said weft be defective. 5

3. In a shuttle changing loom which stops to effect shuttle change, a center filling stop motion normally effective to stop the loom on any beat on which weft fault occurs and having a shield 10 movable when the loom stops to render the center stop motion ineffective to stop the loom on the first beat after resuming operation, means to expel a depleted shuttle from the loom when the same is stopped for replenishment, a thread clamp 15 to preserve tension of the weft in the shed, replenishing mechanism to place a fresh shuttle in the loom, and means between the center stop motion and the clamp to prevent continued running of the loom after the fresh shuttle has been 20 placed into action if the last pick laid by the expelled shuttle is defective.

4. In a shuttle changing loom which stops to effect shuttle change, means to expel the depleted 25 shuttle and replace the same with a fresh shuttle and then resume weaving operations, a center stop motion effective to detect the condition of weft in the shed on all beats of the loom except the one immediately following the resumption of weaving operation, a thread clamp to preserve 30 tension of the weft in the shed, and means independent of the center stop motion between the center stop motion and the clamp to detect the condition of the last pick laid by the expelled shuttle and prevent continued loom running after 35 replenishment if said last pick laid by the expelled shuttle is defective.

5. In a shuttle changing loom which stops to effect shuttle change, discharge means to expel the depleted shuttle and replace the same with 40 a fresh shuttle and then resume weaving operations, a center stop motion effective to detect the condition of weft in the shed on all beats of the loom except the one immediately following the resumption of weaving operation after shuttle 45 changing, a thread clamp to preserve tension of the weft in the shed, and a side stop motion on that side of the loom adjacent the discharge means between the center stop motion and the clamp, said side stop motion effective to detect 50 for weft on alternate beats of the loom and effective to prevent continued running of the loom after shuttle change if the last pick laid by the expelled shuttle is defective.

6. In a shuttle changing loom which stops to 55 effect shuttle change, means to replace a depleted shuttle with a fresh shuttle while the loom is stopped and then resume weaving, a lay which is at rest during the time that the depleted shuttle is expelled from the loom, a thread clamp movable 60 by the means into engagement with the stationary lay, said engagement causing the clamp to catch and hold the weft of the outgoing shuttle and preserve the tension of the weft in the shed.

7. In a shuttle changing loom which stops to 65 effect replacement of the depleted shuttle by a full shuttle, a center stop motion to detect the condition of weft in the shed each beat of the loom except the beat on which weaving is resumed, a side stop motion having a tiltable fork 70 and effective to prevent continuance of loom operation if the pick of weft which is not detected by the center stop motion on the first beat after replenishment is defective, and a thread clamp to preserve the tension of the weft in the shed, 75

the tiltable fork being between the fabric and the thread clamp, the side stop motion effective to prevent continued running of the loom if the clamp fails to grasp a weft should the last pick laid by the outgoing shuttle be short, and said clamp catching the thread of the outgoing weft

and drawing the same across the tiltable fork, the side stop motion thereby being rendered ineffective to stop the loom because of the fact that the last pick laid by the outgoing shuttle is complete.

LEWIS S. VOSE
